UNITED STATES PATENT OFFICE.

JOSEPH H. SANDERSON, OF BABYLON, NEW YORK, ASSIGNOR TO VULCANITE MANUFACTURING COMPANY, OF LINDENHURST, NEW YORK, A CORPORATION OF NEW YORK.

SAFETY-PIN CARD MOUNTING.

Application filed March 12, 1926. Serial No. 94,223.

This invention relates to a safety pin card mounting.

The object of the invention is the production of a safety pin card mounting, wherewith safety pins can be quickly and easily mounted thereon or detached therefrom without the necessity of opening or closing any of the safety pins. The second object of the invention is the production of a mounting of very simple construction and of cheap first cost. The third object of the invention is the production of a safety pin card mounting wherewith one or a plurality of pins or other objects can be easily attached or detached therefrom.

The organization of the invention comprises a flat pierceable supporting card, in which are formed a slot and a pair of openings, to support a U shaped staple. The staple has formed therewith a pair of locking members for supporting safety pins or other objects that are adapted to be suspended.

In the drawings Fig. 1 represents an elevation on an enlarged scale of the safety pin card mounting, exemplifying the invention; Fig. 2 shows a right hand side view of Fig. 1 and Fig. 3 indicates a section of some of the elements of the card mounting about as on the line 3, 3 of Fig. 1.

The mounting in this instance comprises the pierceable supporting card 20, preferably of card board. The card has formed in about its central portion the horizontal slot 21, and spaced from on the opposite sides of said slot are pierced the small openings 22.

A U shaped staple, preferably of metallic wire, is indicated with the central front member 25, from which rearwardly extend at right angles thereto, the central connecting portions 26. The latter join with the rear end members 27, which are parallel to the central member 25. End connecting portions 28 extend forwardly from and at right angles to the members 27. Return locking members 29, normally parallel to the members 27, extend from the connecting portions 28. Each of the return locking members 29, has formed therewith the deflected extension 30, which normally bears against the juncture of its ad-

jacent connecting portion 26 and the central front member 25, and forms with said juncture a detachable locking connection.

The staple forms for the safety pins, the two supporting enclosures, each of which is designated in its entirety by the numeral 32. 55

A plurality of safety pins are each indicated with the body wire 35, the point wire 36, the locking head 37 and the eyelet 38.

In this instance, the locking heads 37 of the safety pins are supported on the return locking members 29 of the staple, so that one member of each head is securely located within one of the enclosures 32. 60

To attach or detach each safety pin from a locking member 29 of the staple, the user may move said member 29, by bearing on its extension 30 to disengage it from the central front member 25 and the connecting portion 26. Or the user may if he so desires, connect or disconnect each safety pin from the members 29, by disconnecting its locking head 37 in the usual manner. 65

The safety pins may be detachably suspended from the return locking members 29, 75 by engaging the eyelets 38 therewith.

Also a plurality of the U shaped staples may be connected to each card 20.

Various modifications may be made in the invention and the present exemplification is to be taken as illustrative and not limitative thereof. 80

Having described my invention what I desire to secure by Letters Patent and claim is:

1. In a safety pin card mounting the combination of a card having a horizontal slot, a U shaped staple supported on the card, said staple comprising a central front member extending through the slot of the card, a pair of central connecting portions extending from said front member, a rear end member extending from each connecting portion, an end connecting portion extending from each rear end member, and a return locking member extending from each end connecting portion locking with said central front member. 85

2. In a safety pin mounting the combination of a card, a staple supported on the card, said staple comprising a central front member, a pair of central connecting portions ex- 100

tending rearwardly from and at right angles to said front member, a rear end member extending at right angles from each central connecting portion, an end connecting portion extending forwardly and at right angles from each rear end member, a return locking member extending from each end connecting

portion and an extension for each return locking member normally locking with the juncture of its adjacent central connecting portion and the central front member. 10

In testimony whereof I affix my signature.

JOSEPH H. SANDERSON.
